UNITED STATES PATENT OFFICE.

GEORGE W. HAGERTHEY, OF LINWOOD, NEW JERSEY.

DISPENSING-CAN.

1,093,325.

Specification of Letters Patent. Patented Apr. 14, 1914.

Application filed September 18, 1912. Serial No. 720,968.

To all whom it may concern:

Be it known that I, GEORGE W. HAGERTHEY, a citizen of the United States, residing at Linwood, in the county of Atlantic and 5 State of New Jersey, have invented certain new and useful Improvements in Dispensing-Cans, of which the following is a specification.

My invention relates to improvements in 10 dispensing cans, and more particularly to an improved air inlet valve therefor, the object of the invention being to provide a valve of this character which permits air to be admitted to the can while the latter 15 is in pouring position, so that the liquid will run freely from the outlet of the can.

A further object is to provide improvements of this character which are especially adapted for use in connection with large 20 cans ordinarily employed for dispensing gasoline and the like.

With these and other objects in view, the invention consists in certain novel features of construction and combinations and arrangements of parts as will be more fully hereinafter described and pointed out in the claims.

In the accompanying drawings: Figure 1 is a view in elevation illustrating my improvements. Fig. 2 is a view in longitudinal section showing the valve in elevation. Fig. 3 is a view in section on the line 3—3 of Fig. 2, and Fig. 4 is a view in section on the line 4—4 of Fig. 2.

35 1 represents a can or other receptacle having a reduced outlet end 2.

3 is the ordinary supporting bail of the can and 4 is my improved air inlet valve which is secured in the side of the can in 40 convenient position to be operated by the thumb of the user, while holding the can at an incline for pouring as seen in Fig. 1.

The valve 4 comprises a cylindrical member 5 on which a cup shaped cap 6 telescopes. The cylinder 5 is provided in one end with an opening 7 which is normally closed by a valve 8. The valve is screwed onto the threaded end of a rod 9. This rod throughout the greater portion of its end is 45 angular, and extends through angular openings in the top 10 of cylinder 5, and in the cap 6, and is securely riveted in the latter.

A coiled spring 12 is interposed between the top of the cylinder 5 and the cap, and 55 is inclosed within the latter. This spring

exerts an upward pressure on the cap and rod 9 to normally hold the valve 8 in closed position.

The lower end of cylinder 5 is screw-threaded and is adapted to screw into a 60 threaded ring 13 formed in the side of the can, and this ring 13 has an annular flange 14 at its inner end upon which a gasket 15 is located, so that the end of the cylinder 5 when screwed against this gasket forms a 65 tight juncture with the can.

The cylinder 5 is provided with a plurality of openings 16 which are normally out of register with openings 17 in the side walls of cap 6, so that dirt and foreign matter are excluded from the valve.

When the cap 6 is forced inwardly to open the valve 8, the openings 16 and 17 are registered, so that the air freely enters the can to allow the liquid to flow freely 75 through the outlet 2. As soon as pressure on the valve is released, the spring 12 returns the cap to the position shown in Fig. 3, effectually closing the openings 16, and rendering the device perfectly tight. 80

My improved valve illustrated in Figs. 2, 3, and 4, may be readily screwed into the can by the employment of a nail or spanner wrench which may be inserted through the openings 16 and 17 and used as a handle to 85 turn the valve either to screw it into place or unscrew it from the can.

Various slight changes might be made in the general form and arrangement of parts described without departing from my invention, and hence I do not limit myself to the precise details set forth, but consider myself at liberty to make such changes and alterations as fairly fall within the spirit and scope of the appended claims. 90

Having thus described my invention, what I claim as new and desire to secure by Letters Patent is:

1. In combination with a dispensing can having a screw-threaded opening therein, a 100 cylindrical member screwed into the opening in the can and having a closed outer end, a cap on the cylindrical portion, a valve normally closing an opening in the inner end of the cylindrical portion, a rod connecting 105 the valve and the cap, a spring interposed between the end of the cylindrical portion and the cap and normally holding the valve in closed position, said cylindrical portion and cap having openings therein normally 110

out of register, and said openings registered when the cap is moved to open the valve, substantially as described.

2. An air inlet device of the character described, comprising a cylindrical member having a closed outer end, and externally screw-threaded at its inner open end, a valve adapted to close said inner open end, a rod secured to said valve and projecting through the closed outer end of said cylindrical member, a cap telescoping on the outer end of said cylindrical member and secured to said rod, a coiled spring around the rod be-

tween the cap and the closed outer end of the cylindrical member, said cylindrical portion and cap having openings therein normally held out of register by said spring, and said openings registered when the cap is moved to open position.

In testimony whereof I have signed my name to this specification in the presence of two subscribing witnesses.

GEORGE W. HAGERTHEY.
